(57) **CLAIM**

The ornamental design for a multi-charger unit for a plurality of communications devices, as shown and described.

DESCRIPTION

FIG. 1 is a top front left perspective view of a multi-charger unit for a plurality of communications devices.

FIG. 2 is top front right perspective view of a multi-charger unit for a plurality of communications devices, with a single communications device drawn in phantom lines.

FIG. 3 a top rear left perspective view of a multi-charger unit for a plurality of communications devices.

FIG. 4 bottom front right perspective view of a multi-charger unit for a plurality of communications devices.

FIG. 5 is a top plan view of a multi-charger unit for a plurality of communications devices.

FIG. 6 is a bottom plan view of a multi-charger unit for a plurality of communications devices.

FIG. 7 is a left side view of a multi-charger unit for a plurality of communications devices.

FIG. 8 is a front side view of a multi-charger unit for a plurality of communications devices; and,

FIG. 9 is a rear side view of a multi-charger unit for a plurality of communications devices.

The phantom lines in FIG. 2 showing a single communications unit in the multi-charger unit is included for purposes of illustrating the multi-charger in a position of use and forms no part of the claimed design.
